UNITED STATES PATENT OFFICE.

WILLIAM L. MORRIS, OF OAK PARK, ILLINOIS.

HYDRAULIC DRAFT CONTROLLER.

Application filed August 5, 1925. Serial No. 48,219.

This invention relates primarily to a thermostat placed in the smoke flue which operates a water valve of a hydraulic ram, utilizing the small travel and power of the thermostat to handle the small valves, which admit water of sufficient quantity and pressure to handle the draft controlling device with ample reserve power to insure dependability. Other objects of the invention will

10 appear hereinafter.

In the accompanying drawing, Fig. 1 shows in section the hydraulic controller as attached to the smoke flue, with thermostat, damper and check, also the lower portion 15 of fuel burner and waste water connections and the connection to the different controls; and Figs. 2, 3, 4, 5 show the starting and finishing positions of the pull chains operating levers for the three draft controls.

20 In carrying out this invention, the quantity of water used is very small and would be a negligible expense if wasted, but where humidifiers are used, they should be constantly supplied with a similarly small quantity and this controller serves as a constant means of supplying this water without the uncertainties arising in use of needle valve control. There are three means of controlling draft; by regulating the amount of air 25 that passes through the grates which is commonly termed the draft control; by regulating the freedom that gases may discharge from the furnace which is known as damper control; and the regulation of the intensity 30 of draft, by means of the check which admits air direct to the smoke flue.

The usual method of control is to set the damper so it will prevent waste of fuel as would be the case of too strong draft when 40 the other controls are set for full draft; the regulating is done by opening more or less either the draft or the check while the other control is closed. This system is that ordinarily employed both for automatic or 45 hand control and is wasteful, slow in responding to higher heat demands and causes smoke to discharge from fire door opening when the door is opened, due to the chilling 50 of the smoke flue and chimney by having the check open which reduces the draft intensity. The check is essential only for extreme conditions such as burning a big charge of loose, highly combustible material, but for the ordinary, regular conditions, 55 the check should not be in operation as a

control, the control being by damper and draft, the draft being entirely closed before the damper even starts to close.

The system here shown and described complies with the demands for highest efficiency. 60 The entire range of control is from full shut off draft position with check open, damper and draft closed, to full draft on position with check closed and damper and draft full open,—a complete cycle of controller 65 movement starting from full shut off high heat position is as follows; as heat in flue drops through the first $\frac{1}{3}$ of its controlling range, it closes the check gradually and in accordance with the temperature drops until 70 the check is closed, then upon reaching the second $\frac{1}{3}$ of the controlling range, the damper starts to open and continues to open until the temperature has dropped $\frac{2}{3}$ its range and damper is full open and as the 75 temperature starts to drop in its third $\frac{1}{3}$ of the controlling range, the draft starts to open and continues to open until the full temperature range is reached and then the draft is full open; as heat in the flue rises 80 and passes by the low point of temperature range (which may be, say 150 degrees F.) then the draft starts to close and is closed at the beginning of the second $\frac{1}{3}$ of range when the damper starts to close and is fully 85 closed at end of this second $\frac{1}{3}$ of range when the check starts to open and is fully open when the high point of the range is reached.

The draft is always entirely shut whenever the damper is closed or partially closed and whenever the check is more or less open. This is essential to avoid escape of gases. Every small change in temperature of flue 90 gases causes a corresponding small change in the draft control. There are two distinctly waste water discharges carried to the humidifiers or ash pit, the one from the hydraulic motor which discharges under 95 some pressure, enough to back up in the leakage drain and overflow, also a separate drip line to carry off the gravity flow leakage drips.

Referring now more particularly to the drawing, a smoke flue 1 connects the fuel 105 burner with the chimney; the ash pit of furnace is shown at 2 with grates 3, a fire pot 4, a fire door 5, an ash door 6, a draft control door 7, an humidifier 8 with an overflow 9, and drip connection 10 to the ash 110

pit 2. A damper 11 oscillates approximately 90 degrees together with its axis shaft 12 and its operating lever 13 which has a crank pin 14. A check door 15 is hinged at 16 to its frame 17 with lever arm 18. The thermostat has two iron expansion members 20 and two brass expansion members 21 secured in pairs with rivets 22. The inner end of the thermostat is supported by extension 23 in a hole in flue 1. The flue 1 has an opening communicating with a flue extension box 25 having an end cover 26.

A double valve body 27 has a pressure valve 28 and a waste valve 29, both seating at their upper ends, with a port 30 to the hydraulic operator and discharge port 31. A valve operating lever 32 is constructed as a drip guide with pins in loose holes at the lower ends of valves 28 and 29 that allow enough angular movement to open either valve. The tension spring 33 draws the end of this valve lever 32 toward the valve body 27. At other end of the valve lever is loosely pivoted a compression pitman 34 which rests at its lower end in the bottom of a countersunk hole at the end of upper thermostat segment 20.

The water supply line to which connection is made is shown at 36 with a valve 37, a supply tube 38 and union connection 39 to valve body 27. The valve body 27 is connected to the flue extension box with a leg 40 and to the upper head 41 of cylinder 42, the port 30 extending through these connection portions. The cylinder 42 has a piston cup leather 43, an upper piston washer 44, and lower piston washer 45 and a nut at the upper end of a piston rod 46 to join these piston parts. The lower cylinder head 48 has a guide 49 for the piston rod 46 and this piston rod has an inclined feather 50 bearing against which is a roller 51 at the end of a bell crank 52. This bell crank 52 is pivoted at the lower end of a supporting bracket 53 and this bracket is attached at its lower end to the lower cylinder head 48 and at its upper end to the flue extension box 25. A compression link 54 is pivoted at its lower end to one of the holes in the bell crank 52 and at upper end to one of the holes in a temperature setting lever 55. To the right hand end of lever 55 is attached the pivoted nut 56 which has a compression T shaped bolt 57 attached, this bolt supporting the outer end of the thermostat. The outer manually operated end of lever 55 is linked to a weight 59 which is sufficient to balance the weight of the outer end of the thermostat, also the downward thrust of pitman 34 occasioned by spring 33 and enough more to operate the valves without causing a damaging strain to the thermostat.

The flue temperature setting device is located and operable at two or more elevations. An upstairs indicator 60 is the same

as the lower indicator 61 except the lower one has its fastenings at top and carries a guide sheave 62, and hand levers 63 engaging with the different teeth of indicator 60 and 61 which have flue temperature notations opposite the teeth reading, say from 100 at the lowest tooth to 1200 at the highest tooth. The hand levers 63 are secured to a raisable and rotatable rod 64, so the levers 63 can be disengaged from teeth of 60 and 61 and set at some other temperature. Attached to this rod 64 is a collar 65 to which a temperature operating chain 66 is attached, the chain passing over an ordinary sheave 67 and with a weight 68 at its lower end sufficient to keep the slack out of the chain; the connection from this weight 68 to weight 59 is made flexible so that no additional weight other than 59 can be put upon the thermostat.

At lower end of piston rod 46 is a swivel block 70 upon which is pivoted a lever 71 which has a pivot at the right hand end to carry a lever 72 and has a chain 73 attached at other end for operating the check 15. This chain 73 passes over ordinary sheaves 74 and 75 and is attached to the end of check lever arm 18 upon which is a weight 76. The weight 76 is sufficient to balance the check 15 and approximately $\frac{1}{3}$ of the weight and friction of the piston and piston rod and lever 71, plus a sufficient amount to insure certainty of operation when the waste valve 29 is opened. The lever 72 has a damper chain 77 at its left side with a stop ring 78 at its upper end which bears against the housing of a sheave 79. To this ring is attached a horizontal chain 80 which passes over a sheave 81 with a housing the same as that of sheave 79 and a stop ring 82 at its other end. To this ring is attached a chain 83 which is connected to damper 11 at its crank pin 14. Also attached to this crank pin (or the lower end of the chain) is a damper weight 84. This weight produces a greater load on the piston than the check weight 76 so it drops until stop ring 78 bears on the housing of sheave 79 before the check weight 76 can start to drop, and it rises only when the check is closed and chain 73 can travel no further.

To the right hand end of lever 72 is attached a draft chain 85 which passes over ordinary sheaves 86 and 87 and is connected to a weight 88 which is connected at its lower end to draft door 7. This draft weight 88 is heavier on the piston than the damper weight 84 and can be raised only when chains 73 and 77 will travel no further after coming to their stops.

A discharge line 89 receives water under some pressure through the discharge port 31 in the valve body 27 and is carried to and discharges into humidifier 8 or if no humidifier is used, to the ash pit 2. The valves 28

and 29 leak slightly, this leakage passing into the trough shaped valve lever 32 and this lever discharges into a funnel 90 at the upper end of a drip tube 91. The piston cup leather 43 leaks slightly and this leakage runs into a trough 92 which runs around lower cylinder head 48 and discharges through a pipe connection 93 into a T 94 that also receives drip tube 91 and discharges through a drip line 95 to the humidifier 8 or direct to the ash pit 2. The building structural parts are shown as a flooring 96 and floor joists 97 with wood cross pieces 98 attached to joists for supporting sheaves and lower indicator 61.

The adjustment and operation of this controller are as follows:—The thermostat may have a travel of $\frac{1}{2}$ " from the lowest say 100 degrees to the highest permissible pressures 20 say 1200 degrees and to prevent too sudden and wasteful extensive draft control changes, it is necessary to allow a temperature range say of 100 degrees throughout which the draft controls may be in any of 25 the intermediate notched positions. This would require a vertical movement of the thermostat supporting member 57 of about $\frac{1}{4}$ ". The correct travel is obtained by marking the taper on feather 50 and the 30 distance of the pivot centers in levers 52 and 55 such as will give the required amount. The range of travel of indicator rod 64 may be 4" from the 100 degree notch to the 1200 degree and if thermostat travel is $\frac{1}{2}$ ", then 35 the pivots would be set to give the ratio of 1 to 8. Different pivot holes are provided in lever 55 and bell crank 52 to permit different ratios. At one particular point in the vertical travel of pitman 34, both the 40 pressure admitting valve 28 and the discharge valve 29 would be closed, and movement above this point causes valve lever 32 to pivot on valve 28 and against the tension of spring 33 which would open water valve 45 29. A downward movement of pitman 34 would cause valve lever 32 to pivot on waste valve 29 and the supply pressure bearing at the upper end of valve 28, which together with tension of spring 33 would cause the 50 supply valve 28 to open.

The chain operating levers 71 and 72, the piston rod 46 and rod guide 49, also pivot block 70 and pull chains 73, 77 and 85 are shown in Figs. 1, 2, 3, 4, 5. Fig. 2 shows 55 the positions with check 15 open, damper 11 closed, and draft 7 closed:—Figs. 3 and 1 show check closed, damper closed, and draft closed; Fig. 4 shows check closed, damper open, and draft closed; and Fig. 5 shows 60 check closed, damper open and draft open.

When the draft controls go through the range of shutting off the draft they operate in reverse order, as Fig. 5, then Fig. 4, then Fig. 3, and completely off as Fig. 2. The 65 piston travels approximately $\frac{1}{3}$ of its full

travel to operate each of the three controls. The operation of the three draft controls is given in the description of the parts. If the indicator rod 64 is accidentally released or chain 66 breaks, the regulator goes into shut 70 off position. If water pressure in the main 36 is shut off, the regulator cannot raise the temperatures. If any of the 3 draft control weight chains 73, 77 or 85 should break, the controls go to shut off position. The regulator will raise the heat only when the parts are intact, and otherwise will go to safe 75 position.

The novel construction shown can be applied in many forms; the hydraulic cylinder 80 may be long enough for the three control travels and by using a continuous single chain and a pulley at each of the weights 76, 84, and 88, the operation will be the same as that shown. Instead of using two 85 separate valves, a ported piston valve can be passed over the ports. Instead of using chains, the levers 71 and 72 may connect direct with one or more of the three draft controls. Four or more pull chains may be 90 used by further increasing the number of double pull levers. The thermostat may be in the furnace instead of the flue, or it may be just outside of either in a chamber that is responsive to the heat of the products of 95 combustion. The cylinder 42 may be at one side of the flue extension so the thermostat can be readily removed. A lever may be placed at the lower end of the indicator rod 64 and the chain 66 moved by rotation of 100 the handle 63, and rod 64 raised to release it from the locking notch.

I claim:

1. The combination with a fuel burning device and its smoke flue, of a thermostat 105 influenced by the temperature of the products of combustion in the device, a plurality of draft controls, and power means actuated by the thermostat for operating the controls in sequence each control coming to rest before the next one is operated.

2. The combination with a fuel burner and its draft obstructing devices, of an hydraulic power mechanism to operate these devices, and a thermostat operated by the 115 temperature of the products of combustion of the burner for controlling the power mechanism.

3. The combination with a fuel burner, its draft obstructing devices, and a thermostat; of an hydraulic power mechanism to operate said devices and controlled by the thermostat, a humidifier in the heated air passage; and a water connection from the power mechanism to the humidifier.

4. The combination with a hot air heating furnace and its draft obstructing devices, of a thermostat, hydraulic power mechanism to operate the devices and controlled by the thermostat, a humidifier in the heated air 130

- passage, and leakage waste connection from the mechanism to the humidifier.
5. The combination with a fuel burner and its draft obstructing devices, of a thermostat influenced thereby, an hydraulic power mechanism to operate the devices and controlled by the thermostat, and a water connection from the mechanism to the ash pit of the burner.
10. 6. The combination with a fuel burner, its draft obstructing devices and ash pit, of a thermostat influenced thereby, an hydraulic power mechanism controlled by the thermostat for operating said devices, a humidifier in the draft passage, a water connection from the mechanism to the humidifier, and an overflow from the humidifier to the ash pit.
20. 7. The combination with a fuel burner and its draft obstructing devices, of an hydraulic power mechanism to operate the devices, a thermostat operated by the heat from the burner to control the mechanism, the mechanism including an inlet and an outlet hydraulic valve, and means whereby the same movement of the thermostat closes one valve before opening the other.
30. 8. The combination with a fuel burning device and its smoke flue, of a thermostat influenced by the temperature of the products of combustion in the device, a plurality of draft controls, power means actuated by the thermostat for operating the controls in sequence, the different controls including means for causing different loadings on the power means so that a lighter operated control will have its full travel before the heavier loaded control will start to move.
40. 9. The combination with a fuel burner and three draft obstructing devices, a single driver therefor and an hydraulic regulator mechanism for operating the three devices from the driver each device coming to rest before the next is operated.
45. 10. The combination with a fuel burner and three draft obstructing devices, of a single driver therefor, an hydraulic regulator for operating the three devices from the driver and comprising a lever pivoted to the driver with a connection at one end to one of the draft obstructing devices, and another lever pivoted at the other end of the first mentioned lever with a connection at one end to the second obstructing device and at the other end of the third obstructing device.
50. 11. The combination with a fuel burner and its draft obstructing devices, of an hydraulic power mechanism to operate the devices, a floating thermostat placed in the outgoing products of combustion, and a valve mechanism actuated by the thermostat to control the hydraulic power mechanism.
60. 12. The combination with a fuel burner and its draft obstructing devices, of an hydraulic power mechanism to operate the de-
- vices, a floating thermostat placed in the outgoing products of combustion, and a valve mechanism comprising a plurality of valves with a variable point of reaction actuated by the stress of the thermostat.
70. 13. A construction in accordance with claim 12 including means for adjustably fixing the point of reaction of the said valve mechanism.
75. 14. A structure in accordance with claim 12 comprising means in connection with a valve mechanism for positioning the point of reaction thereof in fixed relation to the movement of the hydraulic mechanism.
80. 15. A structure in accordance with claim 12 comprising means for varying the point of reaction, said means consisting of a lever having two supports, one resting upon the movable hydraulic power mechanism, and the other adjustably set in a fixed position.
85. 16. The combination with a fuel burner and a draft obstructing mechanism, of a condition maintaining mechanism including a thermostat that is affected by the heat of fuel burning, means for operating the condition maintaining mechanism in unison with the movement of the draft obstructing mechanism, and means for altering the set range of travel of the condition maintaining mechanism with relation to the obstructing mechanism.
90. 17. The combination with a fuel burner and a draft obstructing mechanism, of a thermostatic mechanism affected by the heat of fuel burning, means for operating the mechanism in unison with the movement of the obstructing mechanism, means for setting and locking the range of travel of the mechanism with relation to the obstructing mechanism, said means comprising a rod adjustable and movable endwise having a plurality of operating mechanisms therefor.
100. 18. The combination with a fuel burning device, of an air draft shutoff to the ash pit thereof, an air admitting check in the smoke flue, and a damper in the smoke flue between the check and the fuel burning chamber, a thermostat located in the flue between the damper and the furnace, an hydraulic mechanism to control the draft, a valve mechanism actuated by the thermostat and also by the movement of the hydraulic mechanism, and hand operated means for moving the thermostat into closer engagement with or further from the valve mechanism.
105. 19. The combination with a fuel burning device and its draft controls, of a thermostat actuated by the heat from the burning fuel, an hydraulic motor for operating the draft controls, a valve controlled by the thermostat which admits liquid to the motor, and means comprising weights for the draft controls so that they will operate separately in sequence to shut off draft and will operate
110. 115. 120. 125. 130.

in the reverse order to increase the draft each control coming to rest before the next one is operated.

20. The combination with a fuel burning device and its draft controls, of a thermostat actuated by the heat from burning fuel, an hydraulic motor for operating the draft controls, a valve controlled by the thermostat

for admitting liquid to the motor, the draft controls being provided with weights for operating them in sequence, and retrieving mechanism between the motor and the thermostat to keep their movements in the same relative position.

WILLIAM L. MORRIS.
